UNITED STATES PATENT OFFICE.

JOHN PETERSON, OF FARIBAULT, MINNESOTA.

DESIGN FOR A TABLE.

Application filed December 22, 1922. Serial No. 4,680. Term of patent $3\frac{1}{2}$ years.

To all whom it may concern:

Be it known that I, JOHN PETERSON, a citizen of the United States, residing at Faribault, in the county of Rice and State of Minnesota, have invented a new, original, and ornamental Design for Table, of which the following is a specification, reference being had to the accompanying drawing, forming a part thereof.

The figure is a perspective view of a table showing my new design.

I claim:

The ornamental design for a table, as shown.

JOHN PETERSON.
